UNITED STATES PATENT OFFICE

2,555,967

STEAM PRESSING MACHINE WITH VACUUM-
VALVE OPERATING MECHANISM

Isadore Goldman, Brooklyn, N. Y.

Application October 30, 1947, Serial No. 783,060

2 Claims. (Cl. 38—15)

1

The present invention relates to steam pressing machines or apparatus.

In a well known type of steam pressing machine, to which the improvement of the present invention relates, provision is made for applying an air current to the garment or other article, following the application of steam in the pressing operation, primarily for the purpose of drying the garment or reducing the moisture resulting from the application of the steam. The operation for causing the air flow is performed, usually, immediately after the movable presser head is retracted from engagement with the garment on the buck. Heretofore it was necessary for the operator of the machine to operate two separate pedals by two separate operations according to which the operator was required to remove his foot from one of the pedals, after the actuation thereof for retracting the presser head, and thereafter to place his foot on the other pedal for actuating the valve of a steam ejector to induce a flow of air through the garment. It is obvious that the necessity for performing these two separate operations slows down the operation of the machine and involves the expenditure of considerable effort by the operator of the machine.

The primary object of the present invention is to obviate the above mentioned disadvantages and for that purpose to provide the pressing machine with means by which the retraction of the presser head and the actuation of the valve for controlling the application of the air current to the garment can be performed in a single operation.

Another object of the invention is to provide steam pressing machines with means by which the operator can, at his option, perform both operations either by operating one pedal, if he so desires, or by operating the two pedals provided in the machine as heretofore ordinarily constructed.

The above and other objects, features and advantages of the present invention will be fully understood from the following description considered in connection with the accompanying illustrative drawings.

In the drawings:

Fig. 1 is a side view partly in elevation and partly in section of a known type of pressing machine provided with means embodying the present invention;

Fig. 2 is a plan view of the pedals of the machine shown in Fig. 1;

Fig. 3 is a perspective view of parts of the ma-

chine including the mechanism embodying the present invention;

Fig. 4 is a sectional view on the line 4—4 of Fig. 3.

Referring now to the drawings in detail, there is shown a steam pressing machine or apparatus which, except for the mechanism embodying the present invention, is of known construction, machines of this type but without the mechanism embodying the present invention being in wide use. Said machine comprises, as usual, a frame 10 having at the front thereof the stationary buck 12 and having a companion movable presser head 14 carried by the arm 16 which is pivotally mounted on the frame as indicated at 18. The usual openings or perforations for the flow of steam from the buck and for the flow of air into the buck are indicated at 19 in Fig. 3, a portion of the padding material 21 on the buck being cut away to show some of these openings. As usual, arm 16 is weighted as indicated at 20. A pedal 22 and mechanism associated therewith are provided for moving arm 16 for pressing the head 14 against the garment or other article on buck 12 in the pressing operation. More particularly pedal lever 22 is pivoted at 24 and is pivotally connected to a link 26 which in turn is pivotally connected to a lever 28, the latter being pivoted on the frame as indicated at 30. Lever 28 is pivotally connected to a link 32 and the latter is pivotally connected as indicated at 34 to a toggle lever 36. The latter has one end pivotally mounted at the pivot 24 and has its opposite end pivotally connected to the companion toggle lever 38. A pad block 39 is carried by link 32 for pressing against toggle lever 36 in the usual way in pressing head 14 against the garment on the buck. A member 40 is pivoted to arm 16 as indicated at 42 and is pivotally connected to toggle lever 38 as indicated at 44. A control rod 46 is connected to member 40, as in the usual pressing machine of this type, for regulating the pressure of the toggle mechanism 36, 38 on arm 16 and through the latter on presser head 14 when said toggle is straightened pursuant to the depression of pedal 22. Machines of this type also include pedals such as those indicated at 46, 48, 50 and 52 which are all pivotally mounted on a stationary shaft 54, each of said pedals being spring retracted, as usual, the compression spring for pedal 48 being indicated at 56 in Fig. 1. It will be understood that a similar spring is provided for each of the pedals 46, 50 and 52. It will be noted that the presser head operating pedal 22 operates against the tension of spring

58. Pedal 48 is operable, when depressed against the compression spring 56, to raise pedal 22 and thus break the toggle 36, 38 for retracting the presser head 14. Pedal 48 is provided with the usual block pad 57 for engaging the pedal lever 22 to raise the latter. Pedal 46 is utilized for controlling the admission of steam into the buck 12 for the application of steam through the usual openings 19 provided therein as indicated in Fig. 3 to the garment or other article in the pressing operation. Pedal 52 is utilized for controlling the operation of a valve for admitting steam into the presser head 14. Pedal 50 is utilized for operating a valve of a steam operated ejector for creating a partial vacuum or suction within buck 12 whereby to cause air to flow through the garment through the openings in the buck. The steam ejector device is indicated at 60 in Fig. 3 and as it is of known construction it requires no description. It will be noted, however, that said device includes a valve casing 62 which includes a normally closed valve having a stem 64. The steam inlet for device 62 is indicated at 65; the air passage from buck 12 to the ejector 60 is indicated at 66, and the exhaust of the ejector is indicated at 68. It will be understood that when the valve in casing 62 is opened steam flows through the ejector and by aspirator action produces a suction or partial vacuum in buck 12 so that air flows into said buck through the above mentioned openings and is exhausted from the buck through pipe 66 by the operation of the ejector 60. The mechanism provided in machines of this type for actuating the control valve of ejector 60 includes a link 70 which is pivotally connected at one end thereof to pedal 50 and at its other end to an arm 72 which is secured to a rock shaft 74 mounted in a part of the frame 10. Rock shaft 74 has an arm 76 fixed thereto for operating a link 78 which is pivotally connected to a lever 80 pivoted at 82 and releasably engageable with the valve stem 64 when pedal 50 is depressed for opening the valve of the ejector 60.

As thus far specifically described, the pressing machine is of known construction and has therefore been described only to the extent necessary to explain the present invention which is embodied in said machine as will now be explained:

In accordance with the present invention, provision is made for opening the valve of ejector 60 by operation of pedal 48 which heretofore was utilized only to initiate the operation of the mechanism for retracting the presser head 14 at the end of the pressing operation following the depression of main pedal 22 for straightening the toggle 36, 38. The means provided for this purpose comprises a member 84 (Figs. 2, 3 and 4) which is fixed at one end thereof to the arm 86 of pedal 48 and which is operatively connected to the arm 88 of pedal 50. More specifically, as here shown, member 84 is secured to the arm 86 of pedal 48 by the bolt 90 and at its opposite end member 84 is bifurcated or forked as indicated at 94 for operative connection with pedal 50, more particularly, with the adjustable stop 94. As here shown, stop 94 is constituted by a nut adjustably carried by a threaded rod or bolt stem 96. The latter is adjustably secured to the arm 88 of pedal 50, being in threaded engagement with the latter and held in adjusted position by a nut 98. Member 96 projects upwardly from the arm 88 of pedal lever 50 and stop member 94 is spaced from the upper surface of said arm whereby the forked end 92 of member 84 has a limited move-

ment relatively to stop member 84 in a direction longitudinally of stem 96. A nut 100 is provided for holding stop member 94 in adjusted position. It will be noted that a lost motion mechanism is thus provided between pedal 48 and pedal 50, and it will be understood that a predetermined movement of pedal 48 in a counterclockwise direction, viewing Fig. 1, is required before member 84 is operable on arm 88 to turn the latter simultaneously in a counterclockwise direction. Accordingly, it will be understood that before pedal 50 can be operated by pedal 48 to open the valve of ejector 60 by actuation of link 70 and the associated elements of the valve actuating mechanism, it is necessary for the operator to depress pedal 48 sufficiently to initiate the retraction of presser head 14 from buck 12. On the other hand it will be noted that the operation for opening the ejector valve for drawing air into the buck through the perforations or openings therein is performed by the operator by continuing to depress the pedal 48, so that the same pedal is operable in a single operation thereof by the operator first to retract the presser head and then to open the ejector valve for inducing the flow of air through the garment and into the buck.

It will be observed that the mechanism provided by the present invention is such as to enable the operator to actuate the ejector valve 60 by direct operation of the pedal 50 conventionally provided for this purpose in machines as heretofore constructed. Thus it will be noted that the ejector valve may be operated either by pedal 48 or by pedal 50 at the option of the operator of the machine, and in this connection it will be understood that operators who prefer, by reason of having been long accustomed thereto, or for any other reason, to operate the pedal 50 for opening the ejector valve may do so should they so desire. In this connection it will be understood that the mechanism of the present invention may be readily attached to pressing machines now in use without objection thereto by operators who insist upon operating pedals 48 and 50 in the old way, notwithstanding the desirable advantages of the mechanism of the present invention.

Various changes in the details of construction and in the arrangement of parts may be made without departing from the underlying idea or principles of this invention within the scope of the appended claims.

Having thus described my invention, what I claim and desire to secure by Letters Patent is:

1. In steam pressing apparatus having a buck provided with openings, a companion movable presser head, means for moving said head in relation to said buck for the pressing operation, means including a control member for retracting said head after the pressing operation, and means operable under the control of a valve for drawing air into the buck through said openings; the combination with said control member of the presser-head retracting means of means operable under the control of said control member for opening said valve, said valve opening means comprising a pedal, and said control member comprising a pedal, said pedals being mounted for pivotal movement about a common axis and being relatively movable about said axis, each of said pedals having an extended arm portion and a depressible pedal portion disposed, respectively, at opposite sides of said axis for movement in opposite directions, and means opera-

tively connecting said control pedal to said valve operating pedal, said last mentioned means comprising a member fixed to one of said arm portions and extending laterally thereof and having a lost motion connection with the arm portion of said other pedal whereby a predetermined movement of said control pedal, sufficient to initiate the retraction of said presser head, is required before said first mentioned valve-opening pedal is operable by operation of said control pedal.

2. In steam pressing apparatus having a buck provided with openings, a companion movable presser head, means for moving said head in relation to said buck for the pressing operation, means including a control member for retracting said head after the pressing operation, and means operable under the control of a valve for drawing air into the buck through said openings; the combination with said control member of the presser-head retracting means of means operable under the control of said control member for opening said valve, said valve opening means comprising a pedal, and said control member comprising a pedal, said pedals being mounted for pivotal movement about a common axis and being relatively movable about said axis, each of said pedals having an extended arm portion and a depressible pedal portion disposed, respectively, at opposite sides of said axis for movement in opposite directions, and means operatively connecting said control pedal to said valve operating pedal, said last mentioned means comprising a member fixed

5 to one of said arm portions and extending laterally thereof and having a lost motion connection with the arm portion of said other pedal whereby a predetermined movement of said control pedal in one direction, sufficient to initiate the retraction of said presser head, is required before said first mentioned valve-opening pedal is operable by operation of said control pedal, and spring means operatively connected to said control pedal 10 for moving the same in an opposite direction to a retracted position following operation of the control pedal for moving the same in said one direction.
